William J. Newman,
By Glenn S. Noble, Atty.

UNITED STATES PATENT OFFICE.

WILLIAM J. NEWMAN, OF CHICAGO, ILLINOIS.

BUCKET-LATCH FOR SHOVELS.

1,347,967.

Specification of Letters Patent.

Patented July 27, 1920.

Application filed August 30, 1918. Serial No. 252,053.

To all whom it may concern:

Be it known that I, WILLIAM J. NEWMAN, a citizen of the United States, residing at Chicago, in the county of Cook and State of Illinois, have invented certain new and useful Improvements in Bucket-Latches for Shovels, of which the following is a specification.

The dipper doors of shovels of the type commonly known as steam shovels, are usually hinged at the back and provided with latches comprising bolts secured to the doors and engaging with sockets in the front of the dipper. When the dipper is full of heavy material such as stone or clay, it requires considerable force to withdraw the bolts to unlatch the doors for dumping. The usual device for operating these bolts includes levers which project downwardly some distance below the bottom of the dipper. In using such shovels, particularly for excavating material where the material is to be dumped into wagons or motor trucks, these downwardly projecting levers require the dipper to be raised a sufficient distance above the wagon or truck body so as to clear the levers. This frequently means that the dipper must be held approximately a foot or more above the box or body when the load is dumped. As these dippers frequently hold from one to five tons, the dropping of this load tends to injure the bodies and also tends to injure the springs of the motor trucks as well as otherwise injuring the same.

The present invention relates to means for unlatching the dipper door. The objects of this invention are to provide a simple and efficient mechanism of this character whereby the bolt may be easily withdrawn and the door unlatched; to provide a mechanism whereby the catch may be operated, which will require little or no head room; to provide a latch operating mechanism whereby the dipper or shovel may be lowered to a point adjacent to the top of the wagon or truck box which is to receive the load, and in some instances the bottom of the shovel may extend into such box; and in general to provide such an improved apparatus as will be described more fully hereinafter.

In the accompanying drawings illustrating this invention;

Figure 1 is a side view of a shovel pro-

vided with my improved latch mechanism; and

Fig. 2 is a bottom plan view of the same. As illustrated in these drawings, the dipper stick or handle 3 and dipper or shovel 4 are intended to represent any ordinary or preferred forms of such devices. The dipper door 5 is hinged to the dipper at 6 and is provided with a bolt 7 which engages with a catch or socket 8 in the usual manner.

In order to operate the bolt 7, I provide a shaft 9 which is mounted in bearings 10 in brackets 11 which are secured to the dipper stick 3 in any well known manner as 70 by means of bolts 12. A chain or cable 13 is secured at one end to the bolt 7 and its opposite end is secured to the shaft 9 so that when the shaft is turned, it serves as a winding drum and the chain or cable 75 will be wound thereon. This shaft is provided with an operating arm 14 which is secured at one end thereof and extends upwardly, as shown in Fig. 1. A rope or cable 15 is connected to this arm and leads 80 to a convenient point to be reached by the engineer or operator. In order to limit the movement of the arm 14, I provide stops 16 and 17 which may be conveniently formed on the bracket 11 or may be adjustably attached thereto. The shaft 9 is also preferably provided with a counterweight to hold it in position to allow the bolt 7 to slide into locking position by gravity. In order to provide such a counterweight, I attach a second arm 18 to the shaft, this arm being provided with a weight 19 which may be formed thereon or adjustably secured thereto.

It will be seen that by means of this arrangement, the operator may lower the shovel or dipper to a point approximately even with the top of the wagon or truck box when the load is to be delivered into such vehicle. Then by pulling on the rope or 95 cord 15, the lever 14 will turn the shaft 9 and wind up the chain 13 and thereby pull the bolt from the socket. On account of the leverage provided, the bolt may be withdrawn by a very slight pull, whereas in the 100 ordinary unlatching devices, it frequently requires the full strength of the operator to pull the latch open. When the latch is released, the door swings down into the 105 wagon or truck body and the load will be 110

deposited therein in a comparatively gentle manner instead of with a shock as is ordinarily done. It will also be noted that this device is beneficial where the load is to be deposited on a dump or otherwise, and not in vehicles. When the load has been dumped and the dipper is swung back to loading position, the counterweight will swing the shaft and its operating lever back to its original position so that the bolt 7 is free to move by gravity into locking position.

It will be noted that the details of construction may be varied for different types of shovels and different dipper arms without departing from the scope of this invention, and therefore I do not wish to be limited to the exact construction or arrangement herein shown and described, but

What I claim and desire to secure by Letters Patent is:

1. The combination with a steam shovel adapted for filling wagons or trucks and having the usual dipper and dipper stick, of a shaft mounted transversely of the stick, a chain from said shaft to the latch bolt for withdrawing the bolt, an upwardly extending arm connected with said shaft, an operating rope connected with said arm,

and stops for limiting the movement of said arm to prevent the free end of the arm from swinging below the shaft.

2. The combination with a dipper and dipper handle, of brackets secured to said handle, a shaft mounted in said brackets, a chain from said shaft to the bolt of the dipper latch, an upwardly extending arm from said shaft, an operator's rope from said arm, stops for limiting the movement of said arm to prevent its swinging below the shaft, and a counterweight secured to said shaft and tending to turn the same to normal position to permit the locking of the latch when the dipper is swung to digging position.

3. The combination with a digging dipper and its supporting handle, of bearings secured to said handle, a winding shaft mounted in said bearings, a chain from the shaft to the door latch for opening the latter, an arm extending upwardly from said shaft, an operating cable for said arm, stops for limiting the movements of said arm, and a counterweight extending upwardly from said shaft, the arrangement being such that all of the parts are substantially above the bottom of the dipper.

WILLIAM J. NEWMAN.
